UNITED STATES PATENT OFFICE.

GEORGE EDWARD GAUNT, OF COVINGTON, KENTUCKY.

LOCK.

1,068,235.

Specification of Letters Patent. Patented July 22, 1913.

Application filed November 15, 1912. Serial No. 731,546.

To all whom it may concern:

Be it known that I, GEORGE E. GAUNT, a citizen of the United States, residing at Covington, in the county of Kenton and State 5 of Kentucky, have invented a new and useful Improvement in Locks, of which the following is a specification.

My invention is an improvement in locks and has for its object, the provision of a 10 simple, inexpensive device of the character specified, having a spring operated bolt, which may be retracted manually or by a key, and which may be locked in extended or retracted position.

15 In the drawings, Figure 1 is a side view of the improvement, with a part of the cover plate broken away, showing the bolt partly extended. Fig. 2 is a side view, with the cover plate removed, and with the bolt fully 20 extended. Fig. 3 is a section on the line 3—3 of Fig. 2. Fig. 4 is a perspective view, from above of the latch lever, and Fig. 5 is a similar view of the operating means for the latch lever.

25 The present embodiment of the invention comprises a casing 1, substantially rectangular in cross section and having an open side, normally closed by a cover plate 2. The plate 2 is held to the casing by a screw 30 3, and the casing is secured in place by screws, (not shown) passing through registering openings 4 in the case and cover.

35 The casing is divided into two compartments by means of a transverse partition 5, and a bolt 6 is slidable in the partition and in one end of the casing. The outer end of the bolt is adapted to extend through an opening 7 in the end of the casing, and the 40 said outer end of the bolt is beveled or rounded on one face, as indicated at 8.

45 The end of the bolt, when extended beyond the casing, is adapted to engage a recess 9, in a hasp 10, which may be secured to the door casing by screws 11. The outer side 12 of the recess is inclined, and the free edge of the said side is thickened and beveled, as shown at 13 to engage the beveled face 8 of the bolt, to push the same inwardly, to permit the bolt to pass the said edge.

50 The inner end 14 of the bolt is cylindrical, while the main portion is rectangular in cross section, and the bolt is provided with oppositely extending lugs 15, 15^a at the junction of the cylindrical portion and the 55 main portion. A collar 16 is secured on the inner end of the portion 14 of the bolt, by

means of a pin 17, and the said portion is 60 slideable in an opening 18 in the partition.

A spring 19 encircles the portion 14 of the bolt, between the collar 16 and the partition, 65 and a spring 20 encircles the said portion, between the lugs 15—15^a and the partition. A key hole 21 is provided in the cover plate 70 of the casing, below the bolt, and an opening 22 is provided in the side of the casing in register with the circular portion of the key hole.

The side of the casing is longitudinally slotted, at 23, and a button or knob 24 is provided with a threaded stem 25, which 75 passes through the slot, and engages an opening in the bolt. By means of the knob or button, the bolt may be retracted.

The key hole is for a key of ordinary construction, having a bit for engaging the 75 lower lug 15, to operate the bolt. When the key is inserted in the key hole, and turned, the bit engages lug 15, and pushes the bolt inwardly. The bolt may be locked against retraction by the key, by means of the cam 80 mechanism to be described. The said mechanism to be described. The said mechanism comprises a cam 26, secured to a stub shaft 27, by means of a screw 28, a washer 29 being arranged between the head of the screw 85 and the cam. The shaft has its inner end abutted against the outer face of the casing side, and the screw is passed through an opening in the wall and is engaged with the end of the shaft. The shaft has a handle 90 30 extending radially therefrom, outside of the casing, and by oscillating the shaft, the cam may be brought into the position of Fig. 2, to lock the bolt from inward movement, and into the position of Fig. 1, where it 95 will not interfere with the movement of the bolt. A latch is also provided for the bolt.

The said latch comprises a lever 31, pivoted to the casing by a screw or pin 32. The bolt is provided with a shoulder 33 facing the 100 cam for engagement by lug 15^a, and the end of the lever adjacent to the lug 15^a is normally forced downward by the free end of a plate spring 34, secured to the casing by a screw 35.

105 The opposite end of the lever from the spring 34 is provided with a pair of longitudinally extending arms 36—36^a, each of which is curved inwardly toward its free end, and the upper arm 36 is of lesser length 110 than the lower arm 36^a. An operating lever 37 is pivoted in a bearing 38 on the upper

end of the case, and the said lever extends through a slot into the casing, and engages between the arms 36—36^a.

The upper end of the lever is enlarged to 5 form an operating handle 39. When the bolt is retracted, as shown in dotted lines in Fig. 1, until the lug 15^a engages the shoulder 33, the spring 34 will prevent the lever lifting, and the shoulder will hold the 10 bolt retracted.

When the upper end of lever 37 is rocked 15 toward the hasp, the lower end thereof engages and depresses the arm 36^a, and lifts the opposite end of the lever and releases the lug 15^a. The retraction of the bolt automatically 20 engages lug 15^a with shoulder 33. The bolt may be operated by the knob 24, or by the key, and may be locked in closed position by the cam, and in open position by the latch.

I claim,

1. A lock comprising a casing, a bolt slide- 25 able longitudinally of the casing, said cas- ing having an opening at one end to permit the bolt to be extended at one end, a trans- 30 verse partition in the casing having an open- ing for the bolt, the inner end of the bolt being cylindrical, oppositely extending lugs on the bolt at the junction of the cylindrical portion therewith, said casing having a key 35 hole below the bolt and adjacent to one of the lugs, a latch lever pivoted above the bolt in the casing and having a shoulder for en- gaging the other lug to lock the bolt in re- 40 tracted position, an operating lever pivoted adjacent to the latch lever and having one end extending into the casing, the latch lever having a pair of arms extending on oppo- 45 site sides of the inner end of the operating lever, a spring normally pressing the latch lever toward the bolt to hold the shoulder in engagement with the lug, and means for locking the bolt in extended position, said means comprising a shaft arranged trans- 50 versely of the casing, a cam on the shaft for engaging the inner end of the bolt to lock it in extended position, a handle on the shaft outside of the casing, a collar on the inner end of the bolt, and springs on the bolt on each side of the partition, one of 55 said springs pressing the bolt outwardly, and the other pressing the bolt inwardly.

2. A lock comprising a casing, a bolt slide- 60 able longitudinally of the casing, said cas- ing having an opening at one end to permit the bolt to be extended at one end, a transverse partition in the casing having an opening for the bolt, the inner end of the bolt being cylindrical, oppositely extending lugs on the bolt at the junction of the cylindrical portion therewith, said casing having a key 65 hole below the bolt and adjacent to one of the lugs, a latch lever pivoted above the bolt in the casing and having a shoulder for engaging the other lug to lock the bolt in

retracted position, an operating lever pivoted adjacent to the latch lever and having one end extending into the casing, the latch lever having a pair of arms extending on opposite sides of the inner end of the operating lever, a spring normally pressing the latch lever toward the bolt to hold the shoulder in engagement with the lug, and means for locking the bolt in extended position, said means comprising a shaft ar- 70 ranged transversely of the casing, a cam on the shaft for engaging the inner end of the bolt to lock it in extended position, a handle on the shaft outside of the casing, and a spring pressing the bolt outwardly. 75

3. A lock comprising a casing, a bolt slide- 80 able longitudinally of the casing, said cas- ing having an opening at one end to permit the bolt to be extended at one end, a transverse partition in the casing having an opening for the bolt, the inner end of the bolt being cylindrical, oppositely ex- 85 tends lugs on the bolt at the junction of the cylindrical portion therewith, said cas- ing having a key hole below the bolt and ad- 90 jacent to one end of the lugs, a latch lever pivoted above the bolt in the casing and having a shoulder for engaging the other lug to lock the bolt in retracted position, an operating lever pivoted adjacent to the latch 95 lever and having one end extending into the casing, the latch lever having a pair of arms extending on opposite sides of the inner end of the operating lever, a spring nor- 100 mally pressing the latch lever toward the bolt to hold the shoulder in engagement with the lug, means for locking the bolt in extended position, and a spring pressing the bolt outwardly. 105

4. A lock comprising a casing, a bolt slide- 110 able longitudinally of the casing, means out- side of the casing for operating the bolt, said casing having an opening at one end through which the bolt may extend, a spring pressing the bolt outwardly, means for lock- 115 ing the bolt in extended position, said bolt having a pair of oppositely extending lugs intermediate its ends in the casing, the cas- ing having a key hole for admitting a key for engaging one of the lugs, and a releas- 120 able latch mechanism for engaging the other to lock the bolt in retracted position, said mechanism comprising a latch lever pivoted intermediate its ends in the casing and hav- 125 ing a shoulder near one end for engagement by the other lug of the bolt to hold the bolt in retracted position, a spring pressing the said end of the lever toward the bolt, an operating lever pivoted on the casing near the other end of the latch lever, said latch lever having oppositely arranged arms be- 130 tween which the inner end of the operat- ing lever engages to swing the said latch lever.

5. A lock comprising a casing, a bolt 135

- slidable longitudinally of the casing, means outside of the casing for operating the bolt, said casing having an opening at one end through which the bolt may extend, a spring 5 pressing the bolt outwardly, means for locking the bolt in extended position, said bolt having a pair of oppositely extending lugs intermediate its ends on the casing, the casing having a key hole for admitting a key 10 for engaging one of the lugs, and a releasable latch mechanism for engaging the other to lock the bolt in retracted position, said mechanism comprising a latch lever pivoted intermediate its ends in the casing and having a shoulder near one end for engagement by the other lug of the bolt to hold the bolt in retracted position, a spring pressing the 15 said end of the lever toward the bolt, and an operating lever engaging the other end of the latch lever for swinging the same, said operating lever extending outside of the casing.
6. A lock comprising a casing, a bolt slidable longitudinally of the casing, means outside of the casing and rigid with the bolt 20 for operating the bolt, said casing having an opening at one end through which the bolt may extend, a spring pressing the bolt outwardly, means disconnected from the bolt for locking the bolt in extended position.
7. A lock comprising a casing, a bolt slidable longitudinally of the casing, means outside of the casing for operating the bolt, 25 said casing having an opening at one end through which the bolt may extend, a spring pressing the bolt outwardly, means for locking the bolt in extended position, said means comprising a shaft journaled transversely of the casing, a cam on the shaft for engaging the inner end of the bolt to prevent inward movement thereof, and a handle on the shaft outside of the casing, said bolt having a pair of oppositely extending lugs, and the casing 30 having a key hole adjacent to one lug for receiving a key to engage the lug to operate the bolt, and releasable means for engaging the other lug to lock the bolt in retracted position.
